UNITED STATES PATENT OFFICE.

SAMUEL G. SEVIER, OF OENAVILLE, TEXAS.

BRUSH.

Application filed August 22, 1925. Serial No. 51,785.

This invention relates to improvements in fountain gravity brushes and contemplates the provision of a novel form of brush to which paint and liquids may be fed and 5 readily and easily cut off therefrom when desired.

Another object of my invention resides in the peculiar and novel construction of the brush per se in providing a casing for 10 receiving and applying the paint to the bristles of the brush and yet providing a mounting within which the inner ends of the brush bristles may be vulcanized or cemented.

15 With the above and other objects in view, the invention further includes the following novel features and details of construction, to be hereinafter more fully described, illustrated in the accompanying drawing 20 and pointed out in the appended claim.

In the drawing:—

Figure 1 is a fragmentary elevation of my brush.

25 Figure 2 is a fragmentary side elevation illustrating the structural details thereof.

Figure 3 is a diagrammatic plan view of the elements forming my invention.

Figure 4 is a perspective of a shut off means.

30 Figure 5 is a fragmentary elevation of a modified form of my invention.

Referring to the drawing in detail, wherein like characters of reference denote corresponding parts, the reference character 10 indicates a brush head having a handle 11 formed integrally therewith, the head including a vertically disposed bore 12 communicating at its upper end with an inlet tube 13 receiving its source of supply 35 through a length of resilient tubing 14 associated with its outer and opposite free end, the bore 12 forming an enlarged portion 15 at its lower end and adjacent the lowermost extremity of the head 10. The head having 40 a substantially reduced portion 16 extending circumferentially around and adjacent its lower end, the purpose of which will be presently apparent.

Received upon the lower reduced portion 45 50 55 16 of the brush head 10 is a relatively flat tubular member 17 extending downwardly an appreciable distance below the end of the reduced portion 16 while the reduced correspondingly shaped relatively flat tubular member 18 conforming with the lower enlarged portion 15 of the vertically dis-

posed bore 12 within the lower reduced portion 16 includes an apertured annular flange 19 upon its upper periphery and secured to the lower free end of the brush head 10 60 through the instrumentality of fastening elements in the form of screws 20.

It will thus be noted from the foregoing description and accompanying drawing that paint or other liquids taken from a 65 source of supply and conducted to the tube 14, the inlet pipe 13 and downwardly within the vertically disposed bore 12 and the enlarged portion 15 communicating therewith in order that brush bristles 21 having their 70 inner ends cemented, glued or otherwise secured within the space thus defined between the tubular members 17 and 18 respectively may receive the paint or other liquids passing through the brush head 10 as and for 75 the application thereof.

In order to provide means for cutting and shutting off the supply of the liquid to be applied, a sleeve 22 is inserted within a transversely disposed opening 23 provided 80 in the upper portion of the brush head 10 and communicating with a vertically disposed bore 12 while the sleeve 22 including registering openings 24 at diametrically opposite sides thereof for registration with 85 the bore 12.

Rotatably mounted within a sleeve 22 and having a vertically disposed bore 25 adapted for selective registration with the openings 24 provided at diametrically opposite sides 90 of the sleeve 22 is a valve 26 having a threaded bore 27 within one end for receiving the threaded shank of a bolt 28 extending through a plate 29 provided upon the outer side of the brush head 10 and frictionally engaging the corresponding periphery of the sleeve 22 and end of the valve 26 in forming a leak proof joint at this end. The opposite end of the sleeve 22 having an apertured annular flange provided thereon and secured to the opposite corresponding outer side of the brush head 10 in providing a bearing surface for an enlarged portion 31 provided upon the corresponding end of the valve 26 from whence 10 extends an operating lever 32.

In the mode of operation of the form of my invention as described and illustrated in the foregoing it is clearly apparent and manifest that paint or other liquids fed 110 to the brush head 10 may be regulated as to the quantity to be applied to the brush

bristles 21 cemented or otherwise secured between the space defined between the tubular members 17 and 18 respectively by the selective registrations of the bore 25 within 5 the valve 26 with respect to the openings 24 arranged at diametrically opposite sides of the sleeve 22 registering with the vertically disposed bore 12 of the brush head 10, according to the use to which the brush is 10 put and the desires of the user.

In Figure 5 of the drawing, I have illustrated a modified form of my invention contemplating the provision of a tubular member 33 arranged upon the upper portion of 15 a brush head 10 corresponding in configuration and the arrangement of the elements so associated to the showing of the form of my invention as previously described, save for the tube or pipe 13 communicating with the 20 vertically disposed bore 12 thereof, in so far as the tube 33 not only forms a handle but further includes a flanged nipple 34 upon its upper end in securing a tube, as indicated at 14 in Figure 2 of the drawing, 25 thereto and applying the paint or other liq-

uids in a similar manner to the operation of the first mentioned form.

The invention is susceptible of various changes in its form, proportions and minor details of construction, and the right is here- 30 in reserved to make such changes as properly fall within the scope of the appended claim.

Having described my invention what is claimed is:—

A fountain brush of the character de- 35 scribed comprising a brush head having a vertically disposed bore therethrough terminating in a relatively enlarged portion adjacent its lower end, a relatively flat tubular member having an apertured annular 40 flange provided upon its upper periphery and secured to the lower free end of the brush head in registration with the enlarged portion of the bore, and a flattened tube received upon the lower free end of the head 45 adjacent the relatively flat tubular member and forming a pocket therebetween, and bristles secured within the pocket.

In testimony whereof I affix my signature.

SAMUEL G. SEVIER.
